UNITED STATES PATENT OFFICE.

MAXIMILIAN BÄUML, OF VIENNA, AUSTRIA, ASSIGNOR TO THE FIRM JAGENBERG-WERKE AKT.-GES., OF DUSSELDORF, GERMANY.

CIGARETTE-PACKING MACHINE.

Application filed November 30, 1925, Serial No. 72,355, and in Austria December 2, 1924.

This invention relates to improvements in cigarette packing machines in which the cigarettes pass from a storage receptacle, the width of which corresponds to the 5 length of the cigarette, into upright compartments and from the latter into the package.

One mode of carrying out the present invention is illustrated by way of example on 10 the accompanying sheets of drawings in which:—

Fig. 1 is a part-sectional elevation of the machine according to the present invention, the section being taken on line 1—1 of Fig. 15 2, and

Fig. 2 illustrates the machine in plan-view.

Fig. 3 is a vertical sectional view through 20 the bottom portion of the storage receptacle. Figs. 4 and 5 are sectional views the sections being taken on lines 4—4 and 5—5 respectively of Fig. 3.

Figs. 6 and 7 illustrate in sectional elevation and in plan view respectively a collecting receptacle, which feeds the cigarettes, coming from the storage receptacle, to the package.

As illustrated in Figs. 1 and 2, the storage receptacles 2 and 2', which are displaced 30 with respect to one another at an angle of ninety degrees, are secured to the frame 1 of the machine by means of arms 3. A shaft 4 is located in the frame 1 and, by means of bevel-wheels 5 and 6, operates a

35 vertically disposed shaft 7, a transverse arm 8 being secured to the upper end of the latter. The said arm 8 is provided with vertically arranged shafts, on which are mounted rollers 9 and 9', adapted to engage radial

40 slots 10, which are provided on the bottom side of a disc 11. The latter is keyed to a stub-axle 12, arranged in the frame 1. The disc 11 is provided with crossed arms 13, which are arranged parallel in pairs and at

45 their inner faces, facing one another, are furnished with grooves, in which are disposed radially slidable collecting receptacles 14. Each storage receptacle 2 and 2' consists of a hopper 15 and a slightly inclined

50 casing 16, the bottom end of which latter terminates closely above the top end of the collecting receptacle. A saddle-shaped baffle-plate 17 is arranged in the hopper 15 a slight distance above the casing 16. In the

55 illustrated embodiment, the casing 16 is sub-

divided into five inclined compartments 18 (Fig. 3), which are separated from each other by intermediate spaces 19. Slides 20, which are arranged in two rows and displaced with respect to one another, are disposed in the upper part of the said intermediate spaces 19. At opposite sides the slides are provided with extensions 21 and 21', which extend through slots in the casing-walls and are secured to frames 23 and 24 by means of screws 22, the said frames sliding on guide-bars 25 and 26, which are attached to the casing. Rods 27 and 28 are pivotally attached to the frames 23 and 24 (Figs. 1 and 4), the said rods engaging eccentric discs 29 and 30, which are mounted on a shaft 31. The latter is arranged in the frame 1 and operated by the shaft 4 with the aid of toothed wheels 32 and 33.

Right through the bottom part of the 75 spaces 19 extend shafts 34, and to one end of the latter are secured cranks 35, whose pins 36 engage the slot 36 of a frame 37, which is arranged at the outer broadside of the frame and is also guided on the bars 25 and 26. The frame 37 is secured to a bar 38, which by means of a roller 40 operates on a cam 39, mounted on the shaft 31. Two levers 41 and 41' are secured to each shaft 34 and during the rotation of the shaft intermittently pass, through slots of the compartment-walls, into the adjacent compartments 18.

The collecting receptacles 14, which are adapted to move closely underneath the casings 16, consist of two U-shaped frames 42 and 42', which complete themselves to form a rectangle and slide in dovetailed grooves of the arms 13 and are furnished with ledges 54 on which rest the ends of the cigarettes, the latter being separated by small partitions 56. The adjacent front sides of the frames 42 and 42' are connected with one another by levers 43 and 43', whose common axis of rotation or pivot 44 is vertically slidable in a slot 45 of the arm 13. The pivots of the levers 43 and 43' are connected by means of tension springs 46. The frame 42 carries a pawl 47, which is subjected to the action of a plate-spring 48 and is furnished with an inclined face, which rests on a bridging member 53, connecting the arms 13. A feed-disc 49 is keyed to the stub-axle and is provided with four contacting faces 50 according to the crossed arrangement of the 100 105 110

pairs of arms 13. A rod 51 is arranged radially slideable on the frame 1 and is continuously forced against the feed-disc 49 by means of a spring 52. To the end of the rod 51 is secured an extension 57, which is movable about an axis, arranged in the longitudinal direction of the said rod, and is continuously maintained in the vertical position by the action of a spring. This extension 57 10 co-operates with the pawl 47.

The arrangement of the drive is such, that during one revolution of the shaft 4, the disc 11 carries out a half rotation and the shaft 31 two complete revolutions. The slides 20 15 and the levers 41 and 41' of the storage-receptacle 2' are operated by the shaft 4 in similar manner as the slides and levers of the storage-receptacle 2.

The machine operates in the following 20 manner:

Filling boxes 55 and 55', provided with sliding bottoms and containing cigarettes, are placed onto the storage-receptacles 2 and 2', and the cigarettes drop from the boxes 25 into the receptacles. In consequence of their weight, the cigarettes slide down the funnel-shaped storage-receptacle, whereby the baffle-plate 17 allows only a comparatively small number of cigarettes to collect above the casting 16. The cigarettes, which entered into the compartments 18, are secured and released alternately by means of the levers 41 and 41', which act on the undermost cigarette. If the levers release the cigarettes, the 30 undermost cigarette in each compartment leaves the latter, while the next cigarette takes its place. At the same time the slides 20 move up and down in opposite directions, whereby the cigarettes arranged above the compartments are slightly shaken, thereby facilitating the passage of the cigarettes into the compartments. In consequence of the hollow space underneath the baffle-plate 17, the cigarettes can clear out of the way. In 35 view of the ratio of the driving wheels and a corresponding arrangement of the cam 39, the levers 41 and 41' release the cigarettes only if a collecting receptacle 14 is at a standstill underneath the compartments. Thereby 40 the undermost cigarettes drop into the compartments of the collecting receptacle formed by the partitions 56 and rest on the ledges 54. In consequence of the intermediate spaces separating the compartments, the 45 collecting receptacle underneath the storage-receptacle 2 is supplied only partly with cigarettes, for instance the 2nd, 4th, 6th, 8th and 10th compartments. Now the collecting receptacle moves on and after having passed through an arc of a circle of 50 ninety degrees it comes to rest below the storage-receptacle 2' and here each of the other five compartments is filled with a cigarette. In order to attain this object the storage-receptacle 2' is displaced in such a man-

ner, that its compartments 18 are disposed above the compartments of the collecting receptacle, which are still empty. The construction of the storage receptacles 2 and 2' and their operation are quite identical. 70

Each of the four collecting receptacles 14, which are intermittently moved through ninety degrees, is half filled in the position I and fully filled in the position II, while in the position III the contents of the receptacle is checked whether it is completely filled by a checking device of known construction, and finally the receptacle comes into the position IV, where the same is emptied. The intermittent movement of the 80 disc 11 with the collecting receptacles 14 is effected by the co-operation between the rollers 9, 9' of the arms 8 and the crossed slots 10 of the disc 11, which essentially corresponds to the operation of the Maltese 85 cross drive. The emptying of the collecting receptacle is accomplished in that, as soon as one receptacle has reached the position IV, the rod 51 leaves the operative surface 50 of the toothed disc 49, jerks forward and 90 takes along the pawl 47, which has come into engagement with its extension 57 during the feed-motion. Thereby the two parts 42 and 42' of the collecting receptacle are pulled apart, so that the cigarettes drop out 95 of the said receptacle. During the movement of the pawl 47 by the extension 57, the former is raised by the bridging member 53, so that on completely opening the collecting receptacle (immediately after the 100 dropping out of the cigarettes), the said pawl is disengaged, and now the spring 46 effects the closing of the collecting receptacle. The cigarettes dropping out of the receptacle drop into a packing case 58, which in the 105 open condition is fed into the proper position underneath the receptacle by an intermittently rotated table 59. Before and after the working operation, the extension 57 110 clears out of the path of the arms 13 owing to its pivotal arrangement.

The machine has the particular advantage, that oval cigarettes can be placed in an inclined position into the packing case, because the same are forced to take up an 115 inclined position owing to the inclined arrangement of the compartments 18 and the compartments of the collecting receptacles 14, which they retain during the dropping out of the collecting receptacles, so that the 120 cigarettes lie in the packing case by partly covering one another.

The checking device, arranged in the position III, may operate on the discharge mechanism either in such a manner, that 125 collecting receptacles, which are not completely filled, are not emptied, but are fed forward, or the said receptacles are emptied but the packages, which are not completely filled, are ejected out of the row. 130

Without departing from the spirit of the invention, the construction of the machine may be varied in many ways. For instance the discharge of the collecting receptacles into the packing cases may be carried out not by a free drop or fall of the cigarettes, but by pushing the same out in an axial direction, which however is already known.

I claim:—

- 10 1. A cigarette packing machine comprising in combination storage receptacles for the cigarettes, collecting receptacles for a certain number of cigarettes, means for intermittently feeding forward the collecting receptacles underneath the storage receptacles, compartments in the latter separated from one another by intermediate spaces, and means in these spaces for periodically releasing the cigarettes contained in the said compartments for permitting or preventing the passage of the cigarettes into the collecting receptacles.
- 15 2. A cigarette packing machine comprising in combination storage receptacles for the cigarettes, collecting receptacles for a certain number of cigarettes, means for intermittently feeding forward the collecting receptacles underneath the storage receptacles, compartments in the latter separated from one another by intermediate spaces, and means in these spaces for periodically releasing the cigarettes contained in the said compartments for permitting or preventing the passage of the cigarettes into the collecting receptacles, and means in the storage receptacles for facilitating the admission of the cigarettes into the compartments.
- 20
- 25
- 30
- 35

3. A cigarette packing machine comprising in combination storage receptacles for the cigarettes, collecting receptacles for a certain number of cigarettes, means for intermittently feeding forward the collecting receptacles underneath the storage receptacles, compartments in the latter separated from one another by intermediate spaces, slides in the intermediate spaces, and means for moving the slides up and down.

4. A cigarette packing machine comprising in combination storage receptacles for the cigarettes, collecting receptacles for a certain number of cigarettes, means for intermittently feeding forward the collecting receptacles underneath the storage receptacles, and compartments in the storage receptacles arranged at an inclination whereby to cause oval-shaped cigarettes to assume a predetermined position therein.

5. A cigarette packing machine comprising in combination storage receptacles for the cigarettes, collecting receptacles for a certain number of cigarettes, means for intermittently feeding forward the collecting receptacles underneath the storage receptacles, inclined compartments in the storage receptacles, and compartments in the collecting receptacles arranged at an inclination whereby to cause oval-shaped cigarettes to assume a predetermined position therein and being alined with the compartments in the storage receptacles.

In testimony whereof I hereunto affix my signature.

MAXIMILIAN BÄUML.
